UNITED STATES PATENT OFFICE.

BRUNO ROSENBAUM, OF BERLIN, GERMANY, ASSIGNOR TO WESTINGHOUSE ELECTRIC & MANUFACTURING COMPANY, A CORPORATION OF PENNSYLVANIA.

OSCILLATION GENERATOR.

Application filed August 26, 1921. Serial No. 495,744.

(GRANTED UNDER THE PROVISIONS OF THE ACT OF MARCH 3, 1921, 41 STAT. L., 1313.)

To all whom it may concern:

Be it known that I, BRUNO ROSENBAUM, a citizen of Germany, residing at 256 Kurfürstendamm, Berlin W. 15, Germany,
5 have invented certain new and useful Improvements in Oscillation Generators (for which I have filed an application in Germany, July 24, 1919; in France March 14, 1921; and in Great Britain January 10, 10 1921, the French application now being Patent 534,574 and the British application now being Patent 157,928), of which the following is a specification.

For the production of undamped electric oscillations, more especially for the transmission of messages, discharge-tubes are frequently employed, which tubes, for the sake of increasing the working-capacity, are connected in parallel. Experience has shown, 15 however, that, by this connection in parallel, the doubled capacity for work that might be expected cannot be realized and further, that frequently disturbing influences between the tubes so connected make 20 themselves felt. The idea of the present invention is based on recognition of the fact that these units, connected in parallel and giving rise to oscillations, cannot in their physical and electrical properties be so similar that their co-operation in parallel is 25 directly possible. The invention aims at the removal of the difficulty indicated by reducing the oscillation producing units to dependence on each other, so that they influence 30 each other. Experiments made in connection with the invention have demonstrated that by its aid constancy and regularity in the oscillations produced may be attained.

40 With reference to the accompanying drawings,

Fig. 1 is a circuit diagram illustrating one embodiment of the invention; and

45 Fig. 2 is a circuit diagram illustrating a modified form of the invention.

A constructional example of the invention is represented in Fig. 1 of the drawing, in which *r* denotes discharge-tubes of the known kind with filaments *k*, auxiliary electrodes *g* and anodes *a*, *b* represents the

current sources in the oscillatory circuits, *c* the oscillatory-circuit of the —say two— discharge-tubes, while the heating-battery for the filaments is not shown.

The influencing of the two discharge-tubes is, according to the invention, effected by connecting the grid-circuit of the one tube with the oscillatory circuit of the other tube, by means of, for example, an induction-coil *i* and in this way causing the one tube to be affected by the oscillations, of the other tube. For the rest, the tubes are, after the usual manner, connected in parallel, that is to say the oscillatory circuits *c* act on the same antenna as shown, the same oscillatory circuit or are in any other way coupled with each other, so as to unite the effects proceeding from each tube.

By this reciprocal influencing action of the discharge-tubes on each other, security is afforded that both are working with the waves which are similar and that disturbances will be excluded.

The two oscillatory circuits *c* need not be arranged separate from each other but they may be united either completely or partially, as shown in Fig. 2, wherein a single oscillatory circuit *C* is common to both discharge tubes.

Having now particularly described and ascertained the nature of my said invention, and in what manner the same is to be performed, I declare that what I claim is:

1. In a generator for the production of undamped oscillations, a plurality of electron devices each comprising a cathode, an anode and a control electrode, an anode circuit including a reactance element for each of said devices, a control circuit including a reactance element for each of said devices, the terminals of said anode circuits being connected respectively to their associated anodes and cathodes, and the terminals of said control circuits being connected respectively to their associated control electrodes and cathodes, the control circuit of each of said devices being coupled to the anode circuit of another of said devices, the direction of said coupling being such that the resulting electromotive forces in the control cir-

cuits are in the direction to cause the several electron devices to keep in phase.

2. The method of coordinating the operation of a plurality of three-element electron devices in a multi-tube oscillator, which consists in varying the potential of the control electrode in each device in accordance with

variations of current in the wing circuit of another of said devices, the direction of said variations being alike for each control electrode simultaneously. 10

In testimony whereof I affix my signature.

BRUNO ROSENBAUM.
